US00D748228S

(12) **United States Design Patent**
Bayyouk et al.

(10) **Patent No.:** **US D748,228 S**
(45) **Date of Patent:** **** Jan. 26, 2016**

(54) **VALVE SEAT**

(71) Applicant: **S.P.M. Flow Control, Inc.**, Fort Worth, TX (US)

(72) Inventors: **Jacob A. Bayyouk**, Richardson, TX (US); **Tugrul Comlekci**, Glasgow (GB)

(73) Assignee: **S.P.M. FLOW CONTROL, INC.**, Fort Worth, TX (US)

(**) Term: **14 Years**

(21) Appl. No.: **29/446,059**

(22) Filed: **Feb. 20, 2013**

Related U.S. Application Data

(63) Continuation of application No. 13/755,217, filed on Jan. 31, 2013, now abandoned.

(51) **LOC (10) Cl.** **23-01**

(52) **U.S. Cl.**

(57) **CLAIM**

The ornamental design for a valve seat, as shown and described.

DESCRIPTION

FIG. 1 is a perspective view of a valve seat showing our new design;

FIG. 2 is a front elevational view thereof, the right side elevational, the left side elevational, and the rear elevational views thereof being the same as the front elevational view thereof; FIG. 3 is a top plan view thereof;

FIG. 4 is a bottom plan view thereof; and,

FIG. 5 is a sectional view thereof taken along line 5-5 of FIG. 3.

1 Claim, 5 Drawing Sheets
